(57) **CLAIM**

The ornamental design for a laundry detergent packaging bag, as shown and described.

DESCRIPTION

FIG. 1 is a perspective view of the laundry detergent packaging bag, showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof.

The broken line showing of portions of the laundry detergent packaging bag is included for the purpose of illustrating environmental structure and forms no part of the claimed design.
